(57) **CLAIM**

The ornamental design for a phone case, as shown and described.

DESCRIPTION

FIG. 1 is a front, top, right side perspective view of a phone case showing my new design;

FIG. 2 is a front, bottom, left side perspective view thereof;

FIG. 3 is a front, top, left side perspective view thereof;

FIG. 4 is a front, top perspective view thereof;

FIG. 5 is a second front, top, left side perspective view thereof;

FIG. 6 is a front view thereof;

FIG. 7 is a back view thereof;

FIG. 8 is a left side view thereof;

FIG. 9 is a right side view thereof;

FIG. 10 is a top view thereof;

FIG. 11 is a bottom view thereof;

FIG. 12 is front, top, right side perspective view thereof, shown in an opened state;

FIG. 13 is a front, top, left side perspective view thereof, shown in an opened state;

FIG. 14 is a front, bottom, right side perspective view thereof shown in an opened state; and,

FIG. 15 is second front, top, right side perspective view thereof, shown in an opened state.

The broken lines depicting portions of the phone case form no part of the claimed design. The broken lines lying on top of claimed surfaces represent stitching that forms no part of the claimed design.

1 Claim, 15 Drawing Sheets
